PROCESS FOR THE PREPARATION OF FERRIFERO COBALTOCHLOROAMINOACETATE

Joseph B. Vaughan, Norwood, Ohio, and Harry M. Leyland, Milwaukee, Wis., assignors to Lloyd Brothers, Inc., Cincinnati, Ohio, a corporation of Ohio

No Drawing. Application December 5, 1955
Serial No. 550,858

2 Claims. (Cl. 260—439)

The present invention relates to novel compounds or complexes which are adapted to promote erythropoiesis (erythrocyte production) and hemoglobin formation in the prevention or treatment of anemia including anemia accompanying pregnancy. More specifically the present invention is directed to improved means for the administration of iron and cobalt when iron and cobalt are indicated in the treatment of anemia.

It is recognized in the treatment of anemias, that cobalt will promote erythropoiesis and that the presence of available iron is necessary, in addition to cobalt, for the synthesis of hemoglobin by erythrocytes or their precursors in the body. See Kato, K., Journal of Pediatrics, pages 385-396 (1937); Rohn, R. J., Bond, W. H., Klotz, L. J., The Journal of the Indiana State Medical Assn. 46, pages 1253-1260 (1953); Coles, B. L., James, U., The Journal-Lancet, 75, page 79 (1955). In the past, anemias of the types specified have been treated by conjoint administration of cobaltous and ferrous salts such as cobaltous chloride and ferrous sulfate. Such treatments have been effective in many cases but treatment has some times been handicapped by the patients' reaction to these inorganic ionic salts which tend to be irritating to the gastro-intestinal tract. The degree of this irritability is an idiosyncrasy of the individual and therefore interferes with treatment in some patients more than others. With patients with low tolerances proper dosages cannot be administered without undue discomfort and the unfavorable action seems in some cases to impair optimum assimilation of cobalt and iron.

The taste or palatability of mixtures of cobalt and iron salts is also nauseating and astringent where liquid preparations are required as in the case of infants or in patients who cannot swallow tablets or capsules. This, coupled with gastro-intestinal irritation poses problems as mixtures of salts in certain instances have proven so unpalatable or so irritating as to prevent patients from accepting this type of medication.

The principal object of the present invention is to provide improved means for administering cobalt and iron in the treatment of anemias substantially free from the disadvantages discussed above.

A more specific object of the present invention is to provide a cobalt-iron complex which is less irritating to the gastro-intestinal tract and more readily acceptable on the basis of palatability than mixtures of cobalt and iron salts previously employed in the treatment of anemias.

Still another object is to provide a process for preparing the cobalt-iron complex characterized by the advantages specified above.

Other objects of the present invention will be apparent as the description proceeds.

The complexes or compounds of the present invention can be readily prepared by heating and fusing a mixture made up of a water-soluble, non-toxic cobaltous salt, a water-soluble, non-toxic ferric salt and an amino acid, particularly the α -amino acids such as aminoacetic acid (glycine) and equivalents thereof including alanine, sarcosine,

2

lysine, glutamic acid and the like. Suitable cobalt salts include cobaltous chloride, cobaltous nitrate, cobaltous sulfate, cobaltous acetate, cobaltous citrate, etc., and suitable ferric salts include ferric chloride, ferric nitrate, etc. The salts where available are preferably employed in their hydrate form, a preferred combination being made up of cobaltous chloride hexahydrate and ferric chloride hexahydrate. The cobaltous and ferric salts and amino acid are employed in amounts to provide a Co:Fe:amino acid ratio of about 1:1:3 to 1:8:24 with about a 1:1:6 to 1:4:17 ratio of Co:Fe:amino acid being generally in the preferred range. Larger ratios of iron and amino acid to cobalt can be employed if desired but are ordinarily not accompanied by an appreciable beneficial result. A particularly stable complex is one in which the ingredients are mixed and fused to provide a complex with a ratio of about 1:2:9 of Co:Fe:amino acid. The following examples will serve to illustrate the invention.

Example I

A mixture containing 0.1 mol (23.8 grams) of cobaltous chloride hexahydrate and 0.2 mol (54 grams) of ferric chloride hexahydrate is first placed in a large evaporating type dish or other suitable container and heated slowly until liquefied. About 0.9 mol (67.5 grams) of amino acetic acid is added to the hot mixture, the resulting mixture mixed well and the heating continued with stirring at a temperature of about 125° C. until the water of hydration has been sensibly expelled and the resulting fused composition forms a solid mass upon cooling.

Example II

A mixture made up of 726 grams of ferric chloride hexahydrate, 150 grams of cobaltous chloride hexahydrate and 804 grams of aminoacetic acid is heated between 110-130° C. for a period of from 3 to 5 minutes so that the mass melts and becomes dark green or blackish in color. If the reaction product or complex does not form a solid on cooling, it is reheated until it turns to a solid on cooling. The complex produced by this process has a Co:Fe:amino acid ratio of about 1:4:17.

Example III

This complex is prepared in accordance with Example II by heating and fusing a mixture made up of 150 grams of cobaltous chloride hexahydrate, 340.3 grams of ferric chloride hexahydrate and 425.4 grams of aminoacetic acid. This complex has a Co:Fe:aminoacetic acid ratio of 1:2:9.

Example IV

This complex is prepared in accordance with Example I by heating and fusing a mixture of hydrate salts made up of 107 grams of cobaltous acetate, 116, grams of ferric chloride and 200 grams of aminoacetic acid. This complex has a Co:Fe:amino acid ratio of 1:1:6.

Example V

This complex is prepared in accordance with Example IV by heating and fusing 125 grams of cobaltous nitrate, 116 grams of ferric chloride and 200 grams of aminoacetic acid.

Example VI

This complex is prepared in accordance with Example IV by heating and fusing 102 grams of cobaltous chloride, 150 grams of ferric nitrate and 200 grams of aminoacetic acid.

Example VII

This complex is prepared in accordance with Example IV by heating and fusing 90 grams of cobaltous chlo-

ride, 100 grams of ferric chloride and 200 grams of alanine.

Example VIII

This product is prepared in accordance with Example IV by heating and fusing 90 grams of cobaltous chloride, 100 grams of ferric chloride and 200 grams of sarcosine.

The order of mixing of the ingredients (cobaltous salt, ferric salt and amino acid) is of no consequence and the reaction can be carried out by heating and fusing any one or two components prior to the addition of the other components. Ordinarily, it is preferred to fuse the salts and then add the amino acid or to fuse all three ingredients simultaneously. The heating or fusing temperature should be sufficient to fuse (melt) the mass and should be carried out with stirring for a sufficient time to provide a complex which forms a solid on cooling. As the salts or at least one salt is preferably in hydrate form the temperature employed should be sufficient to drive off the water of hydration. Temperatures of around 100-250° C. can be employed in many instances with a temperature of about 125° C. being generally preferred. In all cases, however, the temperature employed should be below the decomposition temperature as evidenced by the charring of the amino acid. The optimum fusing temperature and time for a particular mixture can be readily ascertained by preliminary test.

The products prepared in accordance with the present invention can be powdered and combined with inert ingredients according to the practice of the art and compressed into tablets for administration. Such tablets can, if desired, be enteric coated to delay their disintegration in the gastro-intestinal tract where patients are unusually susceptible to gastric irritation. The products can likewise be mixed with inert ingredients according to the practice of the art and filled into hard or soft gelatin capsules for administration to patients. The products can also be dissolved in suitable quantities of water or other common pharmaceutical vehicle in appropriate concentration for administration as a flavored or unflavored elixir, solution, tincture or other liquid product.

The complexes produced in accordance with the present invention are water soluble and have toxicities of the same order as mixtures of the individual cobalt and iron salts used heretofore in the treatment of anemia. The complexes, however, are not mere mixtures of the original ingredients or simple salts of amino acids. This has been established by solubility, freezing point and electrical conductance determinations as well as by chromatographic investigations. It has also been determined that an oxidation-reduction reaction apparently takes place during fusion as evidenced by the fact that the iron introduced in ferric form is present in both ferric and ferrous forms in the final complex. The name "ferriferrocobalto-chloroaminoacetate" has been proposed for the complex made by fusing cobaltous chloride, ferric chloride and aminoacetic acid, although the formula of this complex as well as the other complexes, is extremely complicated and remains undetermined and unknown.

The complexes or fusion compositions produced by the process of the present invention may contain small amounts of inorganic components. These contaminants can be removed, if desired, by the following purification procedure.

Example IX

The fused reaction product prepared in accordance with any of the above examples is first dissolved in a minimum amount of water. Isopropanol (99%) is then

added until no further precipitation occurs. The precipitate is allowed to settle and the supernatant liquid decanted. The oily brownish liquid residue is next dissolved in a minimum of water. Methanol is then added to the solution until no further precipitation takes place. The precipitate is recovered by filtering rapidly through a sintered glass funnel. After washing with two small portions of methanol, the complex is obtained as a grayish, hygroscopic relatively pure product.

Although purification is not required, it has been found when making large commercial batches that traces of some unreacted ferric chloride or like caustic salt may be present as a contaminant in the final complex. To take care of this possibility it is generally preferred in commercial operations to routinely add about 1-5% of sodium citrate to the complexes as sodium salts of this type form harmless, non-irritating compounds with irritating salts such as ferric chloride. In commercial operations it has also been found advantageous to include ascorbic acid (vitamin C) with the cobalt-iron-amino-acid complexes of the present invention to provide a daily dosage of 5 mg. to 1 gram of ascorbic acid.

The complexes of the present invention provide as noted above improved means of administering cobalt and iron when assimilable cobalt and iron are indicated in the treatment of anemia. As they tend to be less irritating and are more palatable than mixtures of cobalt and iron salts used heretofore, the complexes can be used to advantage in place of such mixtures and in the similar dosage units to provide the desired Co:Fe ratio in accordance with established practices in this art.

It will be understood that while the invention for the most part has been illustrated with the cobaltous chloride-ferric chloride-aminoacetic acid complex, that other equivalent cobaltous and ferric salts (non-toxic in the amounts employed) and equivalent amino acids can be used as pointed out above in place of chloride salts and aminoacetic acid. Various other equivalent combinations falling within the scope of the invention will be apparent to those skilled in the art.

The present application is a continuation-in-part of our prior application Serial No. 466,692, filed on November 3, 1954, and now abandoned.

We claim:

1. The process of preparing a cobalt-iron-amino-acid complex which comprises fusing a mixture of cobaltous chloride hexahydrate, ferric chloride hexahydrate and aminoacetic acid at a temperature of about 110-130° C. and for a sufficient time to provide a reaction product which turns to a solid on cooling, the amounts of cobaltous and ferric salts and amino acid in said fused mixture being such as to provide a complex with a Co:Fe:amino acid ratio of 1:1:3 to 1:8:24.

2. The process of preparing a cobalt-iron-amino-acid complex which comprises fusing a mixture of cobaltous chloride hexahydrate, ferric chloride hexahydrate and aminoacetic acid at a temperature of about 125° C. for a sufficient time to provide a complex which turns to a solid on cooling, the proportion of ingredients being such as to provide a complex with a Co:Fe:amino acid ratio of about 1:2:9.
